SHEET 2 OF 2

FIG. 2

APPARATUS FOR THE CONTINUOUS PRODUCTION OF POLYCAPROAMIDE

The present invention relates to apparatus for the continuous production of polycaproamide which is used in the manufacture of manmade fibers and plastics.

A continuous method of producing polycaproamide is known, wherein caprolactam is melted and to it are added a molecular-weight stabilizer comprising an organic acid or derivative or an organic acid in an amount of 0.6 percent by weight of the caprolactam, and an activator, the molten caprolactam being polymerized and low-molecular compounds removed from the obtained melt of polycaproamide under vacuum over a period of 1-6 hours with subsequent condensation and filtration of said low-molecular compounds (cf. *Jour. Chem. Engineering No. 7, 1966*).

A disadvantage of the known method is the high content of low-molecular compounds in the polycaproamide obtained (3-3.5 percent by weight).

Another disadvantage of the known method is the deposition in the condensation system of cyclic oligomers included in the low-molecular compounds removed under vacuum, thus causing interruptions in the operation of said condensation system, and consequently, of the entire installation.

Yet another disadvantage of the known method is the presence of the operation of filtration of low-molecular compounds after their condensation.

It is an object of the present invention to provide apparatus for continuously producing polycaproamide making it possible to reduce the content of low-molecular compounds in the product polycaproamide to 1.3-1.5 percent by weight, prevent the deposition of cyclic oligomers of caprolactam in the condensation system and eliminate the operation of filtering low-molecular compounds.

The above and other objects are achieved according to the invention by the provision of apparatus for continuously producing polycaproamide, wherein an organic acid or its derivative is added to molten caprolactam in the amount of 0.65-2 percent by weight and low-molecular compounds are distilled off under vacuum over a period of 8-16 hours.

In order to prevent the deposition in the condensation system of cyclic oligomers of caprolactam forming part of the low-molecular compounds, said oligomers are decomposed catalytically to monomer caprolactam under vacuum at a temperature of 240-280° C. before condensation of said low-molecular compounds.

A known installation for the continuous production of polycaproamide comprises a number of units connected in accordance with the flow sheet, viz: a unit for melting caprolactam, a unit for mixing molten caprolactam with activator and stabilizer additions, a unit for continuous polymerization of caprolactam, a unit for distilling off low-molecular compounds and a condensation system for the same (cf. *Jour. Chem. Engineering No. 7, 1966*).

A disadvantage of the known installation is discontinuity in its operation due to clogging of the pipes of the condensation system by the deposition of cyclic oligomers of caprolactam.

Another disadvantage of the known installation is the cumbersome nature of the condensation system which consists of an apparatus for condensing low-molecular compounds, filters for coarse and fine purification of the condensate, barometric receivers for caprolactam, and circulating pumps, said elements of the condensation system being connected by pipes.

With the object of preventing the deposition of cyclic oligomers in the condensation system and eliminating the stage of filtration of low-molecular compounds, the installation of the present invention comprises means for melting caprolactam, means for mixing molten caprolactam with activator and stabilizer additions, means for continuous polymerization of caprolactam, means operating under vacuum for distilling off low-molecular compounds, and a means for condensing the vapors of low-molecular compounds, all of said means being connected in series with order given there being a means for catalytic decomposition of cyclic oligomers of caprolactam mounted between the means

for distilling off low-molecular compounds and the means for their condensation.

Said means for the catalytic decomposition of cyclic oligomers of caprolactam comprises a cylindrical tank filled with catalytic agent and heated by a liquid or vapor heating medium.

The invention will now be explained by a description of an embodiment thereof with reference to the accompanying drawings, wherein:

10 FIG. 1 diagrammatically shows an installation, according to the invention, for applying the continuous production of polycaproamide including the stage of catalytic decomposition of cyclic oligomers of caprolactam; and

15 FIG. 2 diagrammatically shows a section through the apparatus for catalytic decomposition of cyclic oligomers of caprolactam included in the above installation.

The installation comprises apparatus 1 for melting caprolactam, apparatus 2 for mixing molten caprolactam with activator and stabilizer additions, pumping unit 3 connected by

20 pipes to apparatus 1 and 2, apparatus 4 for continuous polymerization of caprolactam, pumping unit 5 connected by pipes to apparatus 2 and 4, apparatus 6 for distilling off low-molecular compounds, pumping unit 7 with gear pumps connected to apparatus 4 and 6, screw pump 8 connected to apparatus 6, apparatus 9 for catalytic decomposition of cyclic oligomers of caprolactam connected to apparatus 6 for distilling off low-molecular compounds, apparatus 10 for condensing vapor of low-molecular compounds connected to ap-

25 paratus 9 for catalytic decomposition of cyclic oligomers of caprolactam and to barometric receiver 11 for caprolactam and water.

The installation for application of the continuous production of polycaproamide operates in the following manner.

30 Caprolactam is melted in apparatus 1 which is heated with water and is provided with a stirrer. The molten caprolactam is fed by pumping unit 3 into apparatus 2 which is provided with a stirrer and where there are added to the melt an activator, e.g. distilled water, and an organic acid or derivative of an organic acid as a molecular-weight stabilizer.

The amount of stabilizer is adjusted within the range of 0.62-2 percent by weight of the caprolactam.

The reaction mixture is then fed by pumping unit 5 into apparatus 4 for continuous polymerization where the caprolactam is polymerized in a stream of nitrogen at a temperature of 250-280° C. The melt of polycaproamide thus obtained is fed by pumping unit 7 into apparatus 6 for distilling off low-molecular compounds wherein from a thin layer of the melt,

40 water vapor, caprolactam and its cyclic oligomers are driven off over a period of 8-16 hours at a temperature of 260-290° C. and a vacuum of 2-5 mm. of mercury.

45 As a result of holding the melt under vacuum for a lengthy period of time, caprolactam monomer is distilled off completely from the polycaproamide. Simultaneously the process of blocking the terminal amino- and carboxy groups is practically completed, thus giving a polycaproamide melt in which the molecular weight remains unchanged for a lengthy

50 period of time and the thermodynamic equilibrium between polymer and monomer is not restored.

55 The demonomerized polycaproamide containing 1.3-1.5 percent of low-molecular compounds by weight is discharged from apparatus 6 by means of screw pump 8 and is conveyed

60 for processing into plastics or for spinning into fiber.

The vapor of low-molecular compounds leaving apparatus 6 containing 97 percent by weight caprolactam, 2 percent by weight cyclic oligomers and 1 percent by weight water is passed into apparatus 9 which is packed with granulated

70 catalyst and where there takes place catalytic decomposition of cyclic oligomers of caprolactam monomer.

75 The vapor of caprolactam and water leaving apparatus 9 is condensed in apparatus 10 from which the condensate is passed into barometric receiver 11 and is subsequently regenerated.

The present continuous arrangement for producing polycaproamide can be carried out without the stage of decomposition of cyclic oligomers of caprolactam.

In that case the low-molecular compounds removed from the polycaproamide melt in apparatus 6 are condensed in apparatus 10 and the condensate filtered through coarse and fine filters (not shown in drawing) and passed into the barometric receiver.

Conversion of the cyclic oligomers contained in the low-molecular compounds into caprolactam monomer is carried out in the catalytic decomposition apparatus shown in FIG. 2.

The apparatus for catalytic decomposition of the cyclic oligomers of caprolactam comprises vertical cylindrical vessel 12 with conical top and bottom 13. The apparatus has a heating jacket 14 with inlet and outlet pipes 15 and 16 for liquid or vapor heating medium. The apparatus is supplied with fitting 17 for charging and fitting 18 for discharging catalyst 19 and also inlet and outlet pipes 20 and 21 for low-molecular compounds. When in operation the apparatus is filled with granulated catalyst.

The apparatus operates in the following manner.

A vapor mixture of caprolactam, cyclic oligomers and water is passed into the apparatus through inlet pipe 20 and flows through the layer of catalyst 19, whereupon the cyclic oligomers are decomposed into caprolactam monomer which passes out of the apparatus in vapor form through outlet pipe 21. The apparatus is operated continuously at a temperature of 240-280° C. and a vacuum of 2-5 mm. of mercury.

The present invention will now be illustrated by the following example of the production of polycaproamide.

EXAMPLE

A melt of caprolactam with the addition of 4 percent distilled water and 0.7 percent benzoic acid by weight is polymerized for 18 hours in a stream of nitrogen at a temperature of 260° C.

The polycaproamide thus obtained, which has a relative viscosity of 1.95 in sulfuric acid, is passed into the apparatus for distilling off low-molecular compounds. Distillation is carried out for 14 hours at a temperature of 265° C. and a vacuum of 2-5 mm. of mercury.

The low-molecular compounds distilled off are passed into the apparatus for decomposition of cyclic oligomers and there said oligomers are converted into caprolactam monomer at a temperature of 250° C. and a vacuum of 2-5 mm. of mercury. 10 The vapors of caprolactam and water leaving said apparatus are cooled in the condenser and the condensate passed into the barometric receiver from which it is taken for regeneration.

The polycaproamide obtained, which has a relative viscosity 15 of 2.6 in sulfuric acid and contains 1.3-1.5 percent low-molecular compounds by weight, is sent to a spinning machine to be made into fiber or is processed into plastics.

Though the present invention has been described in accordance with a preferred embodiment, it will be understood 20 by those skilled in the art that there may be changes and modifications of the invention without departing from the spirit and scope thereof.

These changes and modifications are to be considered as falling within the spirit and scope of the invention as defined in 25 the appended claims.

What we claim is:

1. An installation for the continuous production of polycaproamide comprising means for melting caprolactam, means for mixing the molten caprolactam with activator and 30 stabilizer additions, means for continuous polymerization of caprolactam, means operating under vacuum for distilling off low-molecular compounds, means for catalytic decomposition of cyclic oligomers of caprolactam and means for condensation of low-molecular compounds, all of said means being connected in series in the order given.
